UNITED STATES PATENT OFFICE

2,160,973

ADJUSTABLE FLAREBOARDS FOR A PLOW

Louis J. Litchy, Royalton, Minn.

Original application July 15, 1937, Serial No. 153,839. Divided and this application April 30, 1938, Serial No. 205,333

2 Claims. (Cl. 37—46)

This invention relates to adjustable flareboards for the moldboards of plows, the invention being mainly designed for use on snow plows of the V-type, the general object of the invention being 5 to provide flareboards at the upper end of each moldboard which are hingedly connected together and the lower one of which is hingedly connected to the upper end of the moldboard, with means for adjusting the flareboards to prevent the snow or other material passing over the 10 top of the moldboard and to direct such snow to the outer side of the plow. This application is a division of application Serial No. 153,839 filed July 15, 1937.

15 This invention also consists in certain other features of construction and in the combination and arrangement of several parts, to be herein-after fully described, illustrated in the accompanying drawings and specifically pointed out in 20 the appended claims.

In describing the invention in detail, reference will be had to the accompanying drawings wherein like characters denote like or corresponding parts throughout the several views, and 25 in which:

Figure 1 is a top plan view of the upper portion of a plow showing the same equipped with the adjustable flareboards.

Figure 2 is a fragmentary rear view of the 30 upper portion of the plow.

Figure 3 is an enlarged fragmentary perspective view of one set of adjusting means.

Figure 4 is a fragmentary front view of one of the moldboards with the flareboards thereon.

35 In these drawings the numeral 1 indicates the pair of moldboards of a V-shaped snow plow and in carrying out the invention I provide a pair of flareboards 2 and 3 for each moldboard. The board 2 is hingedly connected to the upper 40 end of the moldboard as shown at 4 while the two flareboards are hingedly connected together as shown at 5. These flareboards may be of slightly arcuate shape in cross section with their concave faces foremost.

45 For supporting the flareboards 2 and 3 at the desired angular position of adjustment relative to one another and relative to the associated moldboard 1 there are provided for each pair of flareboards 2 and 3 adjustment devices 13 and 14 respectively.

The adjustment device 13 comprises a lug 6 mounted on the rear face of the moldboard 1 adjacent the upper edge of the moldboard while 50 lugs 15 and 16 respectively are provided on the

rear sides of the flareboards, as shown in Figure 3.

Pivoted to the lug 15 associated with the flareboard 2 are links 18 and 19.

Link 18 is provided adjacent one end thereof with a series of openings 20 adapted to be selectively aligned with an opening in the lug 6 to receive a bolt 21 through the medium of which the flareboard 2 is secured at the desired position of adjustment relative to the moldboard 1.

Link 19 at its free end is provided with a series of openings 22 adapted to be selectively aligned with an opening in the lug 16 to receive a bolt 23 through the medium of which flareboard 3 is held at the desired adjustment relative to its companion flareboard 2.

10 The adjustment device 14 comprises a lever 24 pivoted at one end to a bracket 25 mounted on a web plate 26 secured at the angle between the moldboards 1 rearwardly thereof. As best shown in Figure 2 the free end of the lever 24 is provided with a series of openings 27 adapted to be selectively aligned with an opening in a lug 28 on the flareboard 3 to receive a bolt 29 through the medium of which the lever 24 is adjustably 15 secured to the lug 28 to cooperate with the adjustment device 13 for securing the flareboards at the desired angular positions of adjustment.

Thus it will be seen that each pair of flareboards can be easily and quickly adjusted by the 20 two sets of adjusting means 13 and 14 to different angular positions with respect to each other and with the mold 4.

It is thought from the foregoing description 25 that the advantages and novel features of the invention will be readily apparent.

It is to be understood that changes may be made in the construction and in the combination and arrangement of the several parts, provided that such changes fall within the scope of 30 the appended claims.

Having described the invention, what is claimed as new is:

1. In combination with a moldboard of a plow, 35 a pair of flareboards hingedly connected together at their adjacent edges, means for hinging the lower edge of the lower flareboard to the upper edge of the moldboard and means for adjusting the flareboards on their hinges relative to one another and relative to the moldboard, such adjustment means including lugs on the rear faces of the moldboard and the two flareboards, a pair of levers pivoted to the lug of the lower flareboard, means for adjustably connecting one lever to the lug of the top flareboard and means for 40

adjustably connecting the other lever to the lug of the moldboard.

2. In combination with a moldboard of a plow, a pair of flareboards hingedly connected together at their adjacent edges, means for hinging the lower edge of the lower flareboard to the upper edge of the moldboard and means for adjusting the flareboards on their hinges relative to one another and relative to the moldboard, such adjustment means including lugs on the rear faces of the moldboard and the two flareboards, a pair

of levers pivoted to the lug of the lower flareboard, means for adjustably connecting one lever to the lug of the top flareboard and means for adjustably connecting the other lever to the lug of the moldboard, a support on the moldboard, 5 a lever pivoted to the support, a lug on the upper flareboard and means for adjustably connecting the last-mentioned lever to the last-mentioned lug.

LOUIS J. LITCHY. 10
